ABSTRACT OF THE DISCLOSURE

A process for the alkoxylation of N-methyl-N-hydrocarbylamides comprising electrolyzing a solution of a nitrate salt, an N-methyl-N-hydrocarbyl amide and a lower aliphatic alcohol.

BACKGROUND OF THE INVENTION

This invention pertains to a new method of alkoxylating N-methyl-N-hydrocarbylamides.

In co-pending application S.N. 468,981 of Ross et al., now Patent No. 3,411,997, there is described a process for forming the same compounds which result from the instant process. The process of said co-pending application is more involved. For example, in order to form an N-alkoxymethyl-N-hydrocarbyl amide according to said co-pending application, it is necessary first to prepare an N-lower acyloxymethyl-N-hydrocarbyl amide. The alkoxy derivative is then formed by contacting the acyloxy compound with a primary or secondary alcohol in the presence of a catalytic quantity of a strong mineral acid. The present invention eliminates the formation of the intermediate and directly forms the N-alkoxymethyl-N-hydrocarbyl amide.

SUMMARY OF THE INVENTION

This invention relates to method of preparing N-alkoxymethyl-N-hydrocarbylamides by electrolyzing an electrolyte comprising a solution of a nitrate salt, an N-methyl-N-hydrocarbyl amide, and a lower aliphatic alcohol. The electrolysis results in the substitution of an alkoxy group for a hydrogen on the methyl group of said amide. The nitrate salt can be any organic or inorganic nitrate salt. The preferred nitrate salt is ammonium nitrate. The lower alcohol is a C₁—C₆ alcohol. The hydrocarbyl group of the amide can be a C₁—C₆ aliphatic or aromatic group. The preferred lower amides are N,N-dimethylformamide, N,N-dimethylacetamide and N,N-dimethylbenzamide. Thus, in a more limited sense, the invention relates to a method which comprises anodically electrolyzing a solution of ammonium nitrate in a mixture of a C₁—C₆ aliphatic alcohol and a member of the group consisting of N,N-dimethylformamide, N,N-dimethylacetamide and N,N-dimethylbenzamide.

The N-alkoxymethyl-N-hydrocarbylamides formed by the present process will have the following general formula:

where:

R₁ is a C₁—C₆ alkyl or aryl group,
R₂ is a C₁—C₆ alkyl group, and

R₃ is a C₁—C₈ hydrocarbyl group. Examples of hydrocarbyl groups are ethyl, propyl, phenyl, p-tolyl, cyclohexyl, cyclohexenyl, and cyclopentenyl.

2

The present process results in N-alkoxymethyl-N-hydrocarbylamides directly by an electrochemical route, rather than via a chemical reaction involving the use of an intermediate. Moreover, the yields of the present process are significantly higher than the chemical method of said co-pending application. The compounds of the present process find utility as highly polar, aprotic, organic reaction media; electrolyte solvents; and as solvents for fiber spinning.

DESCRIPTION OF THE INVENTION

Example I.—Formation of N-n-butoxymethyl-N-methylformamide

An electrolysis cell is prepared consisting of a water-jacketed, 200 ml. beaker fitted with a magnetic stirring bar, a thermometer and a Teflon cover to which are attached two platinum electrodes 0.025 cm. thick, 2.5 cm. wide, immersed to a depth of 7 cm. and at a separation of 2 cm. A solution of 0.1 mole ammonium nitrate, 0.97 mole dimethylformamide and 0.81 mole of 1-butanol was electrolyzed until 1.26 Faradays of charge was passed through the solution.

The current was 3 amperes during most of the reaction but was decreased to 1 ampere near the close of the electrolysis. Additional 1-butanol (20 ml.) was added during the course of the electrolysis. The excess was removed with the water pump, and ether was added. The precipitated salt was filtered, and the ether was removed. The residue was fractionated at 0.04 mm. and yielded 74.6 g. of N-n-butoxymethyl-N-methylformamide, B.P. 62°—64°, n_D^{23} 1.4365. The amount of dimethylformamide converted to product was 53%. The yield based on the charged passed was 81.6%. A sample redistilled for analysis had B.P. 61° (0.01 mm.) and $n_D^{23.5}$ 1.4364.

The same product was obtained in only 74% yield by treating N-formyloxymethyl-N-methylformamide with 1-butanol in the presence of a catalytic quantity of hydrochloric acid.

Using exactly the same procedure as Example I with ammonium nitrate, methanol, and dimethylformamide, yielded 52% of N-methoxymethyl-N-methylformamide. Likewise, employing ammonium nitrate, ethanol, and dimethylformamide, yielded 66.8% of N-methoxymethyl-N-methylformamide. Electrolysis of ammonium nitrate, 1-butanol and dimethylacetamide yielded 77.75% of N-n-butoxymethyl-N-methylacetamide. As a final example, the electrolysis of ammonium nitrate, ethanol, and N,N-dimethylbenzamide yielded N-ethoxymethyl-N-methylbenzamide.

Obviously, many modifications and variations of the present invention are possible in the light of the above teachings. It is, therefore, to be understood that within the scope of the appended claims, the invention may be practiced otherwise than as specifically described.

What is claimed is:

1. A method of preparing N-alkoxymethyl-N-hydrocarbylamides of the following formula:

where:

R₁ is a C₁—C₆ alkyl or aryl group
R₂ is a C₁—C₆ alkyl group, and
R₃ is a C₁—C₈ hydrocarbyl group,
by electrolyzing an electrolyte comprising a solution of a nitrate salt, an N-methyl-N-hydrocarbyl amide and an aliphatic alcohol; the electrolysis resulting in the substitu-

tion of an alkoxy group for a hydrogen on the methyl group of said amide.

2. The method of claim 1 wherein the nitrate is ammonium nitrate.

3. The method of claim 2 wherein the amide is a member selected from the group consisting of N,N-dimethylamide, N,N-dimethylacetamide and N,N-dimethylbenzamide.
